UNITED STATES PATENT OFFICE.

VICTOR J. DUPIES, OF DALLAS, TEXAS.

DESIGN FOR AN AUTOMOBILE-RADIATOR CAP.

59,341.

Specification for Design.

Patented Oct. 11, 1921.

Application filed June 7, 1921. Serial No. 475,723. Term of patent 3½ years.

To all whom it may concern:

Be it known that I, VICTOR J. DUPIES, a citizen of the United States, residing at Dallas, county of Dallas, and State of Texas, have invented a new, original, and ornamental Design for an Automobile-Radiator Cap, of which the following is a specification, reference being had to the accompanying drawing, forming part thereof.

The figure is a front elevation of a radiator cap showing my new design.

I claim:

The ornamental design for an automobile radiator cap, as shown.

VICTOR J. DUPIES.
